HEAT EXCHANGER

Walter R. Maguire, Manhasset, and Edwin J. Lockwood, Peekskill, N. Y., assignors to Walter Maguire Company, Inc., New York, N. Y., a corporation of New York

Application October 2, 1940, Serial No. 359,326

3 Claims. (Cl. 257—247)

1

The present invention relates to new and useful improvements in heat exchangers and more particularly to a novel and improved apparatus for the heating or cooling of milk.

Objects and advantages of the invention will be set forth in part hereinafter and in part will be obvious herefrom, or may be learned by practice with the invention, the same being realized and attained by means of the instrumentalities and combinations pointed out in the appended claims.

The invention consists in the novel parts, constructions, arrangements, combinations and improvements herein shown and described.

The accompanying drawings, referred to herein and constituting a part hereof, illustrate one embodiment of the invention, and together with the description, serve to explain the principles of the invention.

Of the drawings:

Fig. 1 is a vertical sectional view showing a typical and illustrative embodiment of the present invention; and

Figs. 2, 3 and 4 are vertical cross-sectional views taken on the lines 2—2, 3—3 and 4—4 of Fig. 1 respectively.

The present invention has for its object the provision of a novel and improved heat exchange unit particularly adapted for the efficient heating or cooling of liquids. A further object of the invention is the provision of an improved heat exchange unit which can be easily and quickly sterilized and has a minimum number of points at which leakage is liable to occur, and which can be kept in service over long periods of time with a minimum of attention, aside from the sterilization necessary. Still another object of the invention is the provision of a tubular heat-exchange unit in which the heat exchange tubes may be made of a highly efficient shape and are permanently and immovably attached to the end walls at the ends of the tubes. The invention also provides an improved tubular heat-exchange unit in which the tubes are capable of relative movement due to differences in expansion without danger of the loosening of packed joints, such as are commonly used.

In accordance with the present invention, and as shown in the illustrative embodiment of the invention, the heat exchange unit comprises a plurality of pairs of liquid conducting tubes, each pair comprising an inner and an outer tube of dissimilar cross section, one of the tubes being adapted to contain the liquid to be treated, while the other of the pairs of tubes is adapted to con-

2

tain the other liquid to which or from which heat is to be transferred. Headers are arranged at each end of the heat exchange unit to provide for communication between the respective tubes to conduct the liquid to be treated and the respective tubes to conduct the heat transferring liquid, without the danger of intermixture of the two liquids, and these headers comprise spaced apart walls, partitions or plates, the outer tubes of the various pairs of tubes being securely attached to the innermost walls, while the inner tubes are similarly attached to an intermediate wall. The outer wall is removable so that unobstructed access may be had to the inner conducting tubes. 5 Preferably, the inner and outer tubes are completely welded at their ends to their respective walls, and the space between these walls serves as a header or conduit for the heat transfer fluid, while the space between the intermediate and outer walls serves as a conduit for the fluid to be treated so that the latter fluid may be circulated in thermal contact with the heat exchange medium. Intermediate the ends of the outer tubes, and preferably close to their central portions, the outer tubes are provided with an expansible corrugated portion of flexible metal so that a portion of the expansion and contraction of the outer tube may be taken up at the central portion of the outer tubes, thereby reducing he 10 amount of movement required at the end walls. In accordance with the illustrative embodiment, the outer tubes are preferably of circular cross section throughout the major portion of their length while the inner tubes are preferably of elliptical cross section so as to increase their surface area relative to their capacity, and at the same time insure a more thorough mixing of the moving liquids due to the increased amount of liquid retarded in flow by the skin friction of 15 the pipe.

It will be understood that the foregoing general description and the following detailed description as well, are exemplary and explanatory of the invention but are not restrictive thereof.

45 Referring now in detail to the typical and illustrative embodiment of the invention shown in the accompanying drawings, there is provided a plurality of inner tubes 10 arranged one above the other in vertical alinement, and each of these inner tubes is surrounded by a somewhat larger tube 11 providing a space for the flow of liquid on all sides of the inner tubes 10. Preferably, the inner tubes 10 are elliptical in cross section with their major axes considerably greater than 50 their minor axes. The inner tubes preferably are

of uniform cross section throughout their length so that they may be easily and thoroughly cleaned and sterilized, while the outer tubes are preferably of a uniform circular cross section throughout the major portion of their length but are provided with reduced and tapering ends of elliptical cross section. These tubes may be made of stainless steel or other suitable material.

At each end of the structure is provided a narrow inner vertical wall 15, and this wall is apertured to receive the ends of the outer tubes 11, these reduced ends preferably being welded to the apertures of the wall 15 so as to provide liquid-tight joints between the tubes and the walls at each end of the unit.

Parallel to the inner walls 15, and spaced slightly to the outside of these walls, are provided narrow intermediate vertical header walls 17, which are suitably apertured to receive the elliptical ends of the inner tubes 10, and these inner tubes 10 are welded to the apertures in walls 17 to provide liquid-tight joints. The space between the inner walls 15 and the intermediate header walls 17 is preferably substantial and is largely dependent upon the volume of liquid to be passed between the tubes 10 and 11, and the ends of the tubes 10 are preferably flush with their respective walls 17.

Means are provided for closing the ends of the tubes 10 so that liquid may be supplied thereto and removed therefrom, and its flow directed back and forth through successive tubes. As embodied, an outer header wall forming a cover plate 20 is provided at the left-hand end of the unit and has a short pipe 24 extending therefrom through which liquid may be supplied to the uppermost tube 10 and another pipe 25 through which liquid may be removed from the lowermost tube. Side and end edge walls 21 shown in section in Figure 2 and in part in Fig. 1 space the cover plate from the vertical wall 17 to provide a liquid passageway therebetween, the edge walls 21 also serving to form a liquid-tight closure between the cover plate 20 and the outer face of wall 17. Between the side edge walls 21, and dividing the liquid passageway into compartments are a plurality of narrow removable webs 23 extending from the cover plate 20 to the vertical wall 17. These are illustratively shown as positioned between the topmost and second tubes 10, between the third and fourth, the fifth and sixth, the seventh and eighth, the ninth and tenth, and the eleventh and last tubes 10, thereby dividing the tubes into pairs so that the liquid discharged from the second tube will be reversed in flow through the third tube, and so forth, although the webs 23 may be otherwise positioned to provide the desired circulation. Also the circulation may be varied by substituting one cover plate for another with the webs 23 in different positions. Or alternatively the webs 23 may be repositioned in their cover so as to provide for a different circulation of the liquid.

At the right hand end of the heat exchange unit a similar cover plate 27 is provided which differs from the one just described in that it is not provided with inlet and outlet pipes 24 and 25, and the partitioning webs 23 are provided between the second and third, the fourth and fifth inner tubes, and so forth, thereby providing a continuous liquid pathway back and forth across the heat exchange unit of the uppermost inner tube 10 to the lowermost inner tube. Cover plates 20 and 27 are secured to their respective vertical walls 17 by means of the studs 28 passing through

apertures in the cover plates, and by the wing nuts 29.

Means are provided for supplying heat transfer medium to the space between the tubes 10 and 11, and this medium may be either a heating or a cooling liquid. For this purpose the vertical wall 15 at the left hand end of the unit is provided with an inlet 30 communicating with the space between walls 15 and 17 near the bottom of the unit, and an outlet 31 similarly positioned but at the top of the unit.

Means are provided for making a liquid-tight seal between the inner and intermediate walls 15 and 17 respectively in order to provide for the circulation of the heat exchange liquid, and these means are preferably side walls 32 extending the length of the unit between the intermediate walls 17 and sealingly attached, as by welding, to walls 15 and 17 along their length at their edges, and inwardly bent at both ends to join each other in arcuate end seals, as shown in Fig. 3, thus completing the closure of the circulation chamber or liquid passageway formed by members 15, 17 and 32. In the circulation chamber thus formed at the left end of the heat exchanging unit thin webs 36 are attached to and have sealing engagement with the four walls of the chamber between the openings to the third and fourth outer tubes, and the openings to the ninth and tenth outer tubes. A similar web 37 is provided in the chamber at the right of the unit between the openings to the sixth and seventh outer tubes.

Thus the heat exchange liquid supplied through the inlet 30 flows through the three lowermost outer tubes 11 into the space at the right hand end of the unit between the walls 15 and 17, and is thence reversely directed through the next group of three outer tubes 11 to the space between the left hand walls 15 and 17. Once again the flow of the heat exchange liquid is reversed and it flows through the third group of three outer tubes 11 to the right hand end of the unit and it is finally reversed so as to flow through the upper group of three tubes 11 to the space between the walls 15 and 17 at the upper end of the unit and thence the heat exchange liquid is discharged through the pipe 31. The flow of the heat exchange liquid is generally and preferably counter to that of the flow of the liquid in tubes 10 to be heated or cooled.

In order to reduce the amount of movement required between the walls 15 and 17, without restricting the relative expansion and contraction of the tubes 10 and 11, the outer tubes 11 are preferably formed in two sections with a slight space between their adjacent inner ends near the center of the tubes, and these adjacent ends are permanently interconnected by means of expandible corrugated sections 35 of thin resilient metal, the ends of these expandible sections being welded or otherwise sealed to the ends of tubes 11. In order to economize on space, the expandible sections 35 are staggered slightly with alternate tubes so as to permit closer spacing of the tubes.

Suitable means are provided to increase the efficiency of the heat exchange unit and for this purpose the entire unit is enclosed at its sides, top and bottom within walls 40 of heat insulating material which lies within walls 32.

As shown in Fig. 1, webs 23 are provided with holes 26 through their thickness in order to provide for the drainage of fluid being treated to the bottom of the unit when introduction of the

fluid into the unit through inlet pipe 24 is terminated, the holes being of sufficiently small diameter so that circulation of the fluid through the tubes 10 will not be materially affected when the unit is in use. The tubes 10 and 11 are slightly inclined from the horizontal in order to impart a certain gravity flow to the fluid within the tubes 10 to aid in circulation when the unit is in use and to effect drainage of those tubes when not in use. As may be seen in Fig. 1, the topmost set of tubes 10-11 is downwardly inclined from adjacent the intake pipe 24 to the right end of the unit, while the next set of tubes 10-11 immediately below is oppositely inclined, the third set being oppositely inclined to the second set, and the remaining sets being similarly disposed with relation to each other.

When it is desired to sterilize the apparatus, it is only necessary to remove the wing nuts 29, the couplings to the pipes 24 and 25, and then the cover plates 20 and 27 may be separately removed and can be thoroughly scrubbed and washed. The webs 23 may also be removed from the cover to facilitate sterilization of the cover plates. With the cover plates removed, free access is afforded to the tubes 10 at each of their ends, and as they are of uniform section throughout their length, they may be thoroughly washed and swabbed or otherwise sterilized.

The invention in its broader aspects is not limited to the specific mechanisms shown and described but departures may be made therefrom within the scope of the accompanying claims without departing from the principles of the invention and without sacrificing its chief advantages.

What we claim is:

1. In a heat exchanger, the combination of a pair of headers; and, superposed closely spaced pairs of nested tubes connecting the headers, the tubes of each pair being of dissimilar contour, the outer tube of each pair being of circular cross section throughout a major portion of its length and having its ends of substantially elliptical cross section whereby close spacing of said pairs of tubes may be effected.

2. In a heat exchanger, the combination of a pair of headers; and, superposed closely spaced pairs of nested tubes connecting the headers, the inner tube of each pair being of uniform elliptical cross section throughout its length, the outer tube being of circular cross section throughout a major portion of its length and being formed of two sections interconnected by a flexible extensible member, the remote ends of said sections being of elliptical cross section with the minor axis of each ellipse lying in the plane of the axes of said tubes.

3. In a heat exchanger, the combination of a pair of header compartments having a common partition wall, a plurality of tubes communicating with one of said compartments, said tubes being circular in cross section throughout a major portion of their length, and a plurality of tubes of elliptical cross section each of which communicates with the other of said compartments and is positioned within a different one of said first mentioned tubes.
